UNITED STATES PATENT OFFICE.

FRANZ MILLER, OF MILAN, ITALY.

MOTOR.

1,103,681.

Specification of Letters Patent.

Patented July 14, 1914.

Application filed July 29, 1913. Serial No. 781,720.

To all whom it may concern:

Be it known that I, FRANZ MILLER, a subject of the King of Italy, residing in Milan, Italy, have invented a new and useful Motor, of which the following is a specification.

5 The present invention relates to multi-cylinder motors, especially explosion motors, with cylinders arranged opposite to one another, in which the conversion of the reciprocating motion to rotary motion is effected by the aid of an undulating cam on which the thrust of each piston is exerted.

10 The object of the present invention is a special type of motor in which the oppositely arranged pistons act on the two opposite rolling surfaces of the cam serving to transform the movement in such a way that the opposite pistons approach each other and recede from each other simultaneously.

15 Thus the motor is balanced and, in the case of two annular co-axial cylinders being used, the volume and the weight of the motor can be reduced to a minimum because the projections of the central cam member can penetrate into the cavities of the two cylinders.

20 The accompanying drawings illustrate by way of example several forms of a motor constructed in accordance with the present invention.

25 Figures 1 and 2 are two axial sections at right angles to each other of one form. Fig. 3 is a cross section on line $x-x$ of Fig. 2; Fig. 4 is an axial section of another form; Fig. 5 illustrates a modification of the means for obtaining the rotation of the motor shaft from the reciprocating movement of the piston, and Fig. 6 illustrates still another form of construction.

30 As will be seen from these illustrations, 40 two annular cylinders 5, 5' coaxial with the shaft 1' are arranged one opposite the other, and between them is mounted, rigid with said shaft 1, a cam plate or rail 1 with an undulating edge, of which plate two opposite faces are intended to receive the thrust of the pistons 4, 4'.

35 The undulations of the cam plate or rail 1 may be of any equal number, and in order that the motor may be balanced, the opposing pistons must approach each other and recede from each other simultaneously. Consequently the points where the action of the pistons is applied on the undulated cam will in this case have a displacement from each other of an angle corresponding to the half of a complete undulation.

In the construction illustrated in Figs. 1-3, the pistons 4, 4' each carry rollers 2, 2' at an angle of 90 degrees from each other, bearing against the central cam 1 which has 60 two complete undulations. The cylinders 5, 5' in which the pistons slide, form the casing which may revolve on shaft 1' by the aid of the tubular support 6. The pistons 4, 4' have projections 7 engaging in a groove 65 8 provided in the outer circumference of the cam 1 for the purpose of maintaining the pistons always in connection with the plate itself while the thrust of the pistons 4, 4' is applied to the cam 1 by means of the rollers 70 2, 2'. The spindles of these rollers are prolonged to form projections 9 penetrating into longitudinal grooves 10 in the casing in 80 such a manner that the pistons are carried around by the cylinders 5, 5' when revolving. 75

The gas mixture or in general the motive fluid on passing through the hollow shaft 1', enters the chamber formed between the two cylinders and the cam 1, and thence passes into the cylinders through inlets 12 provided 80 in the wall of the shaft 1' which are opened and closed by a sleeve 11 rigid with the cylinders 5, 5'.

In a two-cycle engine the mixture is introduced into the chamber during the stroke 85 of the pistons in which they recede from each other. During the following stroke the space between them is diminished and a compression of the mixture is caused in such a manner that the inlets 12 which make communication between the chamber and the cylinders are scarcely open, when the mixture penetrates into these latter, after the exhaust openings 13 have been opened and the gases of the preceding explosion have 95 been discharged. On account of the momentum acquired, the system continues to revolve after the completion of the working stroke of the pistons, and the rollers 2, 2' are compelled to mount the successive inclines of the cam 1 in such a manner that the pistons again advance toward the end of their cylinders and after having closed successively the inlets 12 and the discharge openings 13, the mixture is compressed in 105 the interior of the cylinders. After the explosion the cycle mentioned re-commences. Thus at each explosion the rollers 2, 2' in contact with the summit of an undulation of cam 1 are compelled to descend the incline 110 and give an impulse to the whole system, while on account of the momentum the said

rollers remount the following incline and cause the receding stroke of the pistons.

The construction shown in Fig. 4 differs only in that the cam 1 has four undulations to form a four cycle motor with a speed equal to that of the motor shown in Figs. 1 and 2 or a two-cycle motor having half the speed. In these figures are also shown the details of construction.

10 It is obvious that the motor could, in any case, be so constructed as to form a four-stroke-cycle motor, by arranging the admission and the discharge in the known manner.

In the construction shown in Fig. 5, each 15 of the pistons 4, 4' has, on the edge facing the cam 1, a similar undulating cam 16, intended to come into contact with the cam 1 by the intermediary of rolling members such as balls 17, mounted in any suitable manner 20 on the two opposite faces of the cam 1. In the illustration is shown the position of the pistons after the working stroke and it will be seen that the undulations of the two opposite pistons are arranged at an angle of 25 45° to each other, thus compelling the pistons to recede and approach each other at the same time, being carried with the casing when rotating by means of the rollers 9' arranged to slide in the longitudinal 30 grooves 10'.

In the construction shown in Fig. 6, the pistons have again on their opposing edges an undulating cam 16, but the central cam is replaced by a cross member 1' rigid with the 35 shaft 1' and carrying the pairs of rollers 18 arranged to come in contact with the profiled edges or cams of the two pistons 4, 4' which in this case must have equally arranged undulations, as shown in the illustration to allow of the pistons receding from and approaching toward each other simultaneously, in accordance with the action described above. The carrying around of the pistons by the casing is effected also in this 45 case by the aid of rollers 9' sliding in grooves 10'.

It is evident that since the pistons are held to the casing in such a manner as to be able to move longitudinally with respect to the same without being able to turn, the casing will turn if the central cam is fixed, whereas if the casing is made immovable the central cam member and consequently the shaft 1' will turn.

55 The ignition can be effected by the aid of any number of sparking plugs mounted in the end of the cylinders and suitably connected to a common lead 14 (Fig. 4) connected to a distributor 15 of ordinary type.

60 The profile of the cam 1 or the edges of the pistons must be calculated according to the laws of expansion of the gas, and the number, as well as the form of the undulations will depend on the type of the motor 65 and of the desired speed.

The arrangement by which the two pistons or the two opposing series of pistons exert their thrust on the two opposing sides of a common intermediate cam member permits of a balance motor being obtained having 70 the smallest possible volume and weight in consequence of the complete utilization of the resistance of the members employed and of the space.

What I claim as my invention and desire 75 to secure by United States Letters Patent is:—

1. In a motor, the combination of a pair of opposed cylinders connected together to form the casing of the motor and provided 80 with inlet and outlet ports; a hollow shaft, whereon said cylinders are mounted concentric with each other and with the shaft, adapted for connection to a source of motive-fluid supply, said cylinders and shaft 85 constituting companion parts, one of which is fixed and the other revoluble, and said shaft having ports for communication with the inlet ports in said cylinders during the movement of the said revoluble part; a piston reciprocating in each cylinder; and means co-operating with said pistons to convert their reciprocatory movement into rotary movement of said revoluble part and to cause said pistons to approach toward 90 and recede from each other simultaneously.

2. In a motor, the combination of a pair of opposed cylinders connected together to form the casing of the motor and provided with inlet and outlet ports; a hollow shaft, 100 whereon said cylinders are mounted concentric with each other and with the shaft, adapted for connection to a source of motive-fluid supply, said cylinders and shaft constituting companion parts, one of which 105 is fixed and the other revoluble, and said shaft having ports for communication with the inlet ports in said cylinders during the movement of the revoluble part; a piston reciprocating in each cylinder; a member 110 located between said pistons and provided with a plurality of undulating cam surfaces; and rollers connected with said pistons arranged to bear against said cam surfaces, to convert the reciprocating movement of the 115 pistons into rotary movement of said revoluble part and to cause said pistons to approach toward and recede from each other simultaneously.

3. In a motor, the combination of a pair 120 of opposed cylinders connected together to form the casing of the motor and provided with inlet and outlet ports; a hollow shaft, whereon said cylinders are mounted concentric with each other and with the shaft, 125 adapted for connection to a source of motive-fluid supply, said cylinders and shaft constituting companion parts, one of which is fixed and the other revoluble, and said shaft having ports for communication with 130

the inlet ports in the cylinders during the movement of the revoluble part; a member fixed to said shaft for controlling the opening and closing of said inlet ports; a piston 5 reciprocating in each cylinder; means for preventing rotation of said pistons relative to said cylinders; and means coöperating with said pistons to convert their reciproca-
10 tion into rotary movement of said revoluble part and to cause said pistons to approach toward and recede from each other simultane-
ously.

4. In a motor, the combination of opposed cylinders provided with inlet and outlet 15 ports; a shaft around which the cylinders are mounted, said cylinders and shaft con-
stituting companion parts one of which is fixed and the other revoluble; a piston re-
ciprocating in each cylinder; and means to
20 convert the reciprocatory movement of said pistons into rotary movement of said revoluble part and to cause said pistons to approach toward and recede from each other simultaneously, said pistons coöperating in-

dependently with such means at opposite 25 sides thereof.

5. In a motor, the combination of a pair of opposed cylinders; a shaft around which said cylinders are mounted concentrically with each other and with the shaft, said 30 cylinders and shaft constituting companion parts, one of which is fixed and the other revoluble; a piston reciprocating in each cylinder; and a cam rail interposed between said pistons and with which the latter co-
35 operate independently, to convert the recip-
rocatory movement of the pistons into ro-
tary movement of said revoluble part and to cause said pistons to approach toward and recede from each other simultaneously. 40

In testimony whereof I have signed my name to this specification in the presence of two subscribing witnesses.
